UNITED STATES PATENT OFFICE.

GEORGE E. MARLATT, OF PASADENA, CALIFORNIA.

TYPOGRAPHIC MATRIX AND PRODUCTION OF SAME.

Application filed May 26, 1921. Serial No. 472,833.

To all whom it may concern:

Be it known that I, GEORGE E. MARLATT, a citizen of the United States, residing at Pasadena, in the county of Los Angeles and 5 State of California, have invented new and useful Improvements in Typographic Matrices and Production of Same, of which the following is a specification.

My invention relates, for the purposes of 10 this description, to matrices of the kinds employed in connection with slug casting machines such as the linotype, but it is not necessarily limited to use in such connection, as it is capable of adaptation, in several respects, to matrices employed in connection 15 with typographic machines producing individual letters and characters as distinguished from machines producing a number of characters on a single slug. Broadly 20 stated, its chief objective is to provide for the production of an unlimited number of fractions, as they appear in print, by employing a very limited number of matrices for producing such fractions. Another objective 25 is to provide for a similar economy of matrices employed in producing mathematical or other signs and symbols, or characters of any kind.

Because of the impracticability of meeting 30 the requirements for all possible fraction-forming figure combinations, manufacturing efforts have been confined to producing matrices for only the most commonly-used proper fractions. Therefore, in the 35 practice of typography, various makeshifts must be resorted to when occasion arises for producing an unusual fraction. The result is often a lack of uniformity in style in the printed product. For example, fraction 40 matrices, employing either the usual diagonal or horizontal line dividing the numerator from the denominator, may be available for several fractions appearing in close proximity to each other in a printed product, 45 but if an unusual fraction is required in the same product, the numerator and denominator must be separated by a hyphen, the fraction spelled or some other makeshift resorted to, whereas correct typography dictates uniformity of style in such cases. This invention 50 is concerned with rendering such uniformity readily attainable in all contingencies.

In the accompanying drawings, Fig. 1 55 shows a group of matrices of the kinds provided for in this invention as they would

appear assembled in line for casting a type-slug therefrom, but with the units of the group separated for the purpose of clarity; Fig. 2 shows the casting edge of a duplex or two-character matrix group-unit and the construction thereof; Fig. 3 is a side view of a filling piece employed in the construction shown in Fig. 2; Fig. 4 shows the casting face of a matrix group-unit in which a diagonal line separates the numerator figures from the denominator figures in a fraction, with the diagonal line formed on the insert portion of the matrices and the figures on the body portion thereof; Fig. 5 is a side view of the matrix group-unit shown in Fig. 4 and illustrates optional arrangements in opposite edges thereof for producing the diagonal lines shown in Figs. 4 and 6; Fig. 6 shows the reverse edge of one of the matrices represented by Fig. 4, with the diagonal line formed on the body portion of the matrix in both auxiliary and regular positions for appearance, respectively, either below the numerator or above the denominator 60 figures in a fraction, and with the figures formed on the insert portion of the matrix in auxiliary and regular positions for appearance, respectively, either in the denominator or numeral positions in a fraction; Fig. 7 shows a matrix in which one diagonal line and one figure are carried by the body portion of a matrix and one diagonal line and one figure are carried by the insert portion of the matrix; Fig. 8 shows the casting 65 edge of a matrix of duplex type in which similar figures formed in duplicate on the body portion of the matrix in auxiliary and regular positions appear, respectively, in either the numerator or denominator positions in a fraction, while similar figures formed on the insert portion in auxiliary and regular positions appear, respectively, in either the denominator or numerator positions in a fraction; Fig. 9 shows a duplex 70 Janus-face matrix and may be considered a side view of Fig. 8 and answering the description thereof with respect to its opposite edges, except that the insert at the right relates to means for producing accented letters; Fig. 10 shows a matrix group-unit 75 forming a fraction with one figure in the numerator position and two figures in the denominator position, with two dissimilar figures for selective use formed on the insert, and insert filling-pieces in use in co-operation with the single numerator figure above 80

the two denominator figures; Fig. 11 represents a matrix group-unit of duplex type in regular (left) and auxiliary (right) positions with respect to a base line, with the figures in the body and insert portions of the matrix appearing in either denominator or numerator positions according to the position of the matrix with respect to the base line; Fig. 12 represents a matrix employing two alphabetical characters, one of which may be made to appear in superior position and the other in inferior position according to the position of the matrix with respect to a base line; Fig. 13 represents a modified method of constructing a piece-fraction matrix; Fig. 14 shows opposite edges and a vertical center section of a duplex Janus-faced matrix designed to produce four dissimilar characters; Fig. 15 is a rear elevation of a fragment of the matrix separating and distributing elements of a linotype machine, showing the adaptation thereto of matrices constructed in accordance with these specifications; Fig. 16 is a section on the line 16—16 of Fig. 15; Fig. 17 is a subdivision of Fig. 15; Fig. 18 is a plan view of a tool for converting stock matrices into special-purpose matrices; Fig. 19 is a section on the line 19—19 of Fig. 18, but with the upper portion thereof in changed position; Figs. 20 and 21 are details of Fig. 18. Similar figures indicate similar parts throughout the several views of the drawings.

Linotype matrices in general commercial use are of two kinds with respect to the number of characters on their casting edge, namely single-character and two-character or duplex. An example of the use of duplex matrices is found in the employment of a roman and italic character on the same matrix. By presenting such a matrix in its regular or lower position to the casting slot of a mold, a roman printing character is obtained, and by presenting it in its raised or auxiliary position an italic character is obtained. Fig. 1 illustrates matrices of both single and duplex type, the duplex matrices carrying fractions in both regular and auxiliary positions, and the single-character matrices carrying mathematical signs. The characters above the center of the matrices are in regular position and those below the center are in auxiliary position. Therefore if a matrix is raised with respect to a base line of the casting mold, the auxiliary character will be presented to the casting cavity of the mold and the regular character will be raised above the casting cavity. These relative positions are illustrated in Figs 11 and 12, in which the space between the dotted lines represents the casting slot of a mold. This present invention involves the employment of two similar or dissimilar characters on the casting edge of the body

portion 1 of a duplex matrix and two similar or dissimilar characters on an insert portion 2 of the matrix. Referring again to Fig. 11 it will be seen that with the matrix in regular position, one of the similar characters on the body portion occupies the denominator position of a fraction, and with the same matrix in raised position the other similar character occupies the numerator position. The positions of the similar characters on the insert portion 2 are likewise reversed by raising or lowering the matrix. It will be apparent, therefore, that a duplex matrix so employed has a two-fold usefulness over a single-character matrix, and that twice as many matrices of single character type would be required to obtain similar results. This invention also provides for the use of both edges of a matrix for casting purposes, and such a matrix in duplex type will therefore have a four-fold usefulness. For example, five such matrices, each having a different even number in duplicate on one edge and a different odd number in duplicate on the other edge would produce any fraction having one digit only in the numerator and denominator positions, and would be capable of producing 9×9 or 81 different fractions. Five such matrices would therefore be a complete set for such fractions. Two such sets or ten matrices would produce any fraction having not more than two digits in the numerator or denominator positions, i. e., 99×99 or 9,801 fractions. Three such sets (15 matrices) would produce $9,999 \times 9,999$ or 99,901 fractions. Four such sets (20 matrices) would produce $9,999 \times 9,999$ or 99,980,001 fractions. And in addition, 20 such matrices would be capable of producing fractions having as many as 20 figures in either numerator or denominator, but would be limited as to the number of figures of like value which could be employed, the limitation decreasing with a decrease in the total number of like figures employed in a fraction.

In accordance with this invention, characters other than numbers may be employed in positions corresponding to those of numerator and denominator in a fraction. For example, Fig. 12 illustrates how a single matrix may produce a letter of the alphabet in either superior or inferior position on a type slug. Also a matrix for producing such exponent characters could be provided with dissimilar characters on opposite edges, as, for example, italic characters on one edge and roman letters on the other edge. Also such an arrangement of characters in superior and inferior positions would be capable of producing ornamental, border or other characters in staggered relation by alternating the matrices in regular and auxiliary positions. While it has not been unusual to provide similar or dissimilar characters in

auxiliary and regular positions on a matrix, it is believed that the method above described for causing the characters to appear on a type-slug in inferior or superior position at will is novel. In this connection it may be stated that a character appearing on the upper half or superior position of a thick slug would be in regular or full position on a slug half as thick, still further increasing 10 the range of usefulness of many characters.

A further example of utility of a matrix employing the insert piece is found in the production of accented letters. The accent marks occupy but little space and it is therefore possible to place as many as four of them on one insert for use in duplex matrices, and in connection with single-letter matrices as many as eight, in either case two accent marks appearing on each casting 15 edge of the insert. Thus, in Fig. 9 is shown such an insert designed to be reversed end for end or side for side to produce any one of four different accents either above a letter in regular position or below a letter 20 in auxiliary position. In this manner eight different accented letters may be produced from one edge of a matrix, and with a different letter on the opposite edge the number would be sixteen. And since the same insert 25 may be transposed from edge to edge and from matrix to matrix, ten matrices each having different letters on opposite edges would be capable of producing 160 different combinations of letters and accents. In the case of Janus-faced single-letter matrices there would be ample room for an insert having two accents on each of four edges and ten such matrices and one insert would therefore produce 160 different 30 combinations, with the accents above the letters if the single letters were in regular position and below the letters if they were in auxiliary position. An additional insert piece carrying accent marks differing from those on the first insert would double the 35 possibilities of the ten matrices, producing 320 combinations from the ten matrices and two inserts.

Since accents are frequently too small to 50 be readily read as they appear on the casting edge of thin matrices, they may be duplicated as an index on the side of the insert; likewise the letter on the matrix may also be duplicated to appear and be read in its relation to a selected accent mark. Such indexes are shown in Fig. 9.

In the usual arrangement of linotype molds with relation to the matrices, the upper part of a character, as it appears in 55 print, is of fixed position with relation to the slug produced from the mold, and as the slug increases in thickness according to size of type or space between lines of reading matter, the increase takes place adjacent the 60 lower part of the characters. Therefore it is

not always possible to add an accent mark to the upper edge of a slug. For example, it would be impossible to add an accent above a capital letter as the top of the letter itself is flush with the edge of the slug. A 70 difficulty of this kind may be readily overcome with the use of the insert piece by casting the accent on the lower edge of a slug next above the one on which the accented character occurs. Inserts may be provided 75 with the accents variously spaced from their edges according to the space which is to appear between lines of print; or, the insert itself may be variously and selectively placed in the body of the matrix by means 80 of an instrument hereinafter described.

The method of producing fractions having one digit in the numerator and two in the denominator, or vice versa, is illustrated in Fig. 2. In its regular position such a matrix would produce a fraction with two digits in the numerator and one in the denominator, and in its auxiliary position would produce a fraction with one digit in the numerator and two in the denominator. Since the 90 single digit in such an arrangement would appear on the body portion 1 of the matrix, filling pieces 3 are provided for bringing the matrix to a uniform thickness equal to two of the insert portions 2. Any increase in number of the inserts 2 would necessitate the employment of a corresponding increase in the number of filling pieces or their equivalent in filling pieces of increased thickness. 95

Fractions having diagonal lines separating the numerator from the denominator are sometimes preferred to those having horizontal dividing lines, as for example, when an occasional unusual fraction occurs in a group, the majority of which is provided for by the diagonally-divided fraction matrices in common use. Figs. 4, 5 and 6 show two optional methods for producing such fractions. The diagonal line may be 105 formed on inserts occupying positions in line with either the denominator or numerator of a fraction according to whether they are to appear below the numerator or above the denominator. Such inserts may be of 110 any desired thickness not exceeding the combined thickness of the denominator or numerator matrices with which they are employed. Fig. 4 shows such inserts of three 115 different thicknesses. One edge of the matrix shown in Fig. 5 shows in full lines the insert appearing below the numerator in Fig. 4, and in dotted lines the insert appearing above the denominator. The opposite edge of Fig. 5 in connection with Fig. 6 120 shows the diagonal line appearing on the body portion 1 of the matrix and the digit or cipher on the insert. Thus arranged the diagonal line is below the numerator when the matrix is used in regular position and 130

above the denominator when the matrix is used in auxiliary position. It would also be practicable to provide one diagonal line and on digit or cipher on the body of the matrix 5 and one diagonal line and one digit or cipher on the insert, as illustrated in Fig. 7.

The insert 2 may carry two dissimilar digits either one of which may be made to appear in the numerator position of a fraction 10 by reversing the insert. Fig. 10 illustrates such an arrangement. The same illustration also shows the manner of employing blank inserts as filling pieces where a less number of digits appear on the insert than 15 on the body of the matrix.

A modified form of constructing a matrix for producing piece-fractions is shown in Fig. 13. The upper 2' and lower 1' parts 20 of a matrix thus constructed are separable one from the other for use in co-operation with the opposite portion of any other matrix of similar construction. Such a construction is not readily adaptable to duplex matrices unless one of the characters is of 25 fixed design and position as shown in one edge of the lower portion of Fig. 13, in which case the variable character 2'' would be in service with the matrix in regular position, and the lower or constant character 30 1'' would be in service with the matrix in raised or auxiliary position.

I also provide for utilizing dissimilar characters in opposite edges of solid or one-piece matrices. Hyphen leaders and period 35 leaders for optional use would be a useful combination of the kind; and Fig. 14 shows opposite edges of a duplex matrix carrying 40 four different mathematical signs. It is preferable that matrices carrying such commonly-used characters shall be automatically distributed in the usual manner after use. But a matrix of the usual construction if reversed to present its reverse edge to the mold 45 of a linotype machine, could not be automatically distributed for reasons hereinafter stated. It is therefore a purpose of this invention to provide a matrix which may be used in reversed positions without interfering with its automatic distribution. Viewed 50 in their positions as shown in Fig. 15, after being carried to the distributing elements of a linotype machine, the matrices as heretofore constructed have their carrying lugs 4 flush with the left side of the matrix body 55 and their distributing combinations 5 flush with their opposite side. To prevent more than one matrix at a time being lifted from the distributor box rails 7 into engagement with the distributor screws 8, the matrices 60 are provided with a groove 6 which has heretofore appeared only on that side of a matrix which is flush with the distributing combinations 5. This groove varies in depth according to the thickness of the matrices 65 so as to leave a wall 6'' of uniform

thickness on the lug side of all matrices, and this wall is approximately as thick as the thinnest matrices which are intended to pass through the distributor box. To co-operate with the groove 6 for preventing the lifting of two matrices at a time a blade 9, commonly called the bar point, is carried by the inner end of the combination bar 10 in the distributor box. The space between the bar point and the shoulders 11 on the matrix supporting rails 12 is less than the thickness of two thin matrices and therefore but one matrix at a time may be raised in front of the bar point. It is therefore apparent that thick matrices of the common construction 70 above described could not pass the bar point in their reversed position, for the reason that the groove 6 would be on the wrong side of the matrix and the wall formed by the groove would interfere with the bar point. 75

In order that the matrices may pass through the distributor box in their reversed positions, I provide for constructing them with their lugs 4, their distributing combinations 5 and the wall 6'' between opposite grooves 6 (Fig. 14), all in the vertical center of the matrices and of approximately equal thickness. Therefore with the lugs 4 stopped against the shoulders 11 on the supporting rails 12 and the lugs of a thickness not greater than the distance between the bar point and the shoulders 11, the wall in the same vertical plane with the lugs will not interfere with the bar point in either 100 of their reversed and reversible positions. Matrices thus constructed may be considered an improvement over the usual matrix hereinbefore described regardless of whether they are intended to be reversible as and for the purpose stated, for the reason that with the distributing combination in their center of gravity they will depend perpendicularly from the several combination bars from which they are successively suspended between the casting and distributing positions. The combination distributing teeth of a heavy matrix would be subject to less wear when thus suspended in balance than would result with the teeth on one side of the matrix. When not intended to be reversible the matrices would require the groove 6 on one side only. 105

It will be noted that in the drawings here-with certain matrices are shown provided with distributing teeth 5 and others without such teeth, and that those not having teeth are also without the grooves 6 and have their supporting lugs 4 the full thickness of the matrix, thus simplifying their 110 construction. Such simplified matrices are not designed to be carried to the distributor box but by reason of the omission of the teeth are deposited miscellaneously in a receptacle (not shown), known as the inter- 115 120 125 130

mediate channel quad-box. But if provided with teeth they engage the first organ of the distributor (not shown) and are distributed either in channels of a magazine or carried 5 beyond the channels and deposited miscellaneous in a receptacle known as a pi or sorts box. In either case if they follow each other in rapid succession and are of considerable thickness they frequently interfere 10 one with another in entering the channels leading to the magazine or sorts box. To obviate this condition, I construct such thick matrices so that they will appear with double the usual space between them when 15 suspended from the distributor bar 14 and engaged by the distributor screws 8. With this object in view, the matrices are provided with a shoulder 19 adjacent their lower edges and on one or both sides accord- 20 ing to whether the matrices are intended to be reversible. The matrix lift 16, which rises and falls with the lift lever 15 under control of a cam 13 on the upper rear distributor screw 8 is provided as usual with 25 a shoulder 18, the horizontal angle of which shoulder engages the lower edge of the matrices and raises them into engagement with the distributor screws. The vertical angle of the shoulder 18 is longer than the verti- 30 cal angle of the special shoulder 19 on the matrix; therefore the lift will engage only the shoulder on the matrix when the matrix rests on the rails 12, and this engagement will not occur until the lift has moved up- 35 wardly a distance equal to the vertical depth of the shoulder on the matrix. The resultant initial movement of the matrix is not sufficient to place it in engagement with the distributor screws or to cause its lugs to 40 clear the shoulders 11 on the rails; therefore such initial movement serves merely to cancel a stroke of the lift. When the lift again rises following this canceling stroke, its upper edge will engage the horizontal shoul- 45 der of the matrix and raise the matrix into engagement with the distributor screws as shown in dotted lines in Fig. 16. The matrices will therefore appear only in alternate spirals of the distributor screws and will 50 have double the usual distance and time be- 55 tween them for accomplishing the purpose above set forth. When matrix group-units of the kind shown in Fig. 2 are intended to pass through the distributor box, the fill- 60 ing pieces 3 must be provided with a slot 6' to permit the composite matrix to pass the bar point 9.

Although in these specifications my improvements are described in connection with the commonly employed single-character and duplex-character matrices, the improvements are not limited to use in such connections. In my Patent No. 1,310,487, issued July 22, 1919, means are shown and de- 65 scribed for utilizing matrices having as

many as four characters on each edge, and the features of this invention are readily applicable to such matrices. Therefore, wherever reference is had herein to characters in auxiliary position on a matrix, such reference may be understood to mean any one or more of several auxiliary positions. In order that full advantage may be had of the improved piece-matrices herein de- 70 scribed, I provide means whereby such matrices may, in an emergency, be made from any stock matrices carrying the requisite character parts. For example, the insert pieces 2 provided with accent marks may be on hand in sufficient quantity, but a partic- 75 ular letter of a particular font, requiring an accent, may not be provided with the recess for receiving the insert. For any such emergency involving accented or other characters or the blank filling pieces, heretofore 80 described, the punching tool illustrated in Figs. 18 to 21 may be employed. The matrix 1 is held in a frame 20 which is adjustable by means of screws 21 with reference 85 to a scale 22 on the beveled edge of a bank- 90 ing block 23, in order to place the matrix in any desired position between the upper 24 and lower 25 die elements. The station- 95 ary die 25 is embedded in a base 26, and the punch 24 is secured in a plunger 27 carried 100 by a swinging arm 28 mounted on a shaft 29. The arm 28 also carries a detent 30 which enters a recess 31 in the base and serves to position the punch 24 in accurate 105 register with the die 25. The plunger 27 has a groove 32 which is engaged by a plun- 110 ger arm 33, confined in a slot 34 of the arm 28. A spring 35 keeps the arm normally in contact with a stop pin 36 for the purpose of holding the plunger in position to be struck with a mallet to drive the punch through the matrix 1. The downward 115 stroke of the plunger is limited by contact of the mallet with the arm 28, and the extracted portion of the matrix is extruded 120 through an opening 37 in the base 26. To remove the frame 20 which confines the matrix, the arm 28 is forced upward against a spring 38, thus disengaging the detent 30 and permitting the arm to be swung to a position such as shown in Fig. 18. The frame 20 is then readily removable edgewise 125 across the recess 31 for the purpose of removing the matrix. A receptacle 39 formed in the base 26 is normally closed by a cover 40 integral with the arm 28 and substitute dies and punches may be kept therein for security against loss. Suitable plunger tools may also be provided for swaging the lugs 4 of the matrices, which frequently become sheared or worn. In such use the detent 30 is made to enter one of the recesses 41 in the base for positioning the plunger above a selected lug. When the detent is thus engaged it also locks the frame 20 in a fixed 130

normal position, but the frame 20 may be reversed endwise for placing opposite lugs beneath the plunger. Thus, when it is desired to swage opposite short lugs, for example, the frame would be reversed and the 5 detent moved from one to the other of the recesses 41. When the detent is in the central recess 31 the frame is free to be adjusted endwise by means of the screws 21 according to the font size or other characteristics 10 of the matrix which is to be punched, but transversely it is held in constant position between the detent and the banking element 23.

15 When a matrix of the common, usual type is punched in opposite edges or for other reasons is to be reversed in the distributor box as hereinbefore described, it is necessary to cut the usual font distinguishing notch 20 42 in the opposite side of the longitudinal center of the matrix. In order that the additional notch may be accurately located, index or guide notches 43 may be formed on the frame 20 and the desired notch located 25 relative to a selected guide notch.

Having described my intention, its use and production, what I claim as new and desire to secure by Letters Patent of the United States, is as follows:—

30 1. A typographic matrix having characters in regular and auxiliary positions on the body portion thereof, a recess between said regular and auxiliary positions capable of receiving an insert part, and an insert part 35 for said recess having characters in position to co-operate with the characters on the body portion of the matrix for forming composite characters in both of said regular and auxiliary positions.

40 2. A typographic matrix having characters in regular and auxiliary positions on opposed edges of the body portion thereof, a recess between said regular and auxiliary 45 positions capable of receiving an insert part, and an insert part for said recess having characters in position to co-operate with the characters on the body portion of the matrix for forming composite characters in both of said regular and auxiliary positions.

50 3. A typographic matrix having constant and variable portions, co-operating character-parts on each of said portions, the character-part on the constant portion being positioned to produce a corresponding character in superior position on a printing slug, and the character on the variable portion being positioned to produce a character in 55 inferior position on a printing slug.

4. A Janus-faced typographic matrix having constant and variable portions, co-operating character-parts on each of said portions, the character-part on the constant portion being positioned to produce a corresponding character in superior position on a printing slug, and the character on the 60

variable portion being positioned to produce a character in inferior position on a printing slug.

5. A Janus-faced typographic matrix having constant and variable portions, co-operating character-parts on each of said portions, the character-part on the constant portion being positioned to produce a corresponding character in inferior position on a printing slug, and the character on the 70 variable portion being positioned to produce a character in superior position on a printing slug.

6. A typographic matrix divided into upper and lower interlocking portions, each of 80 said portions carrying one part of a variable printing character and each portion being capable of association with a selected opposite portion for the purpose of varying said printing character.

7. A typographic matrix having constant and variable portions, characters in regular and auxiliary positions on the edge thereof, one part of the character in regular position being on the constant portion and the other on the variable portion of the matrix, and one part of said character in auxiliary position being on the constant portion and the other part on the variable portion of 90 the matrix.

8. A typographic matrix having constant and variable portions, characters in regular and auxiliary positions on opposite edges thereof, one part of the character in regular position being on the constant portion and the other on the variable portion of the matrix, and one part of said character in auxiliary position being on the constant portion and the other part on the variable portion of 100 the matrix.

9. A typographic matrix composed of a constant and a variable portion for forming a composite character, one part of said character being on the constant portion of the matrix and the other part on the variable 110 portion, the variable portion having different character parts on different edges thereof and each capable of being placed in selective co-operation with the character-part on the constant portion of the matrix.

10. A typographic matrix having a character in regular and auxiliary positions thereon, the character in one of said positions being capable of producing a printing character in superior position on a type-slug and the character in the other of said positions being capable of producing a printing character in inferior position on a type-slug, selectively, according to whether the matrix is employed in regular or auxiliary 120 position.

11. A composite typographic matrix having a constant portion carrying one or more character-parts thereon, and a variable portion having dissimilar character-parts on 125

opposite sides of its center and capable of being reversed to place either of such character-parts in character-forming relation to a character-part on the constant portion of the matrix.

12. A typographic matrix for producing variable composite characters on a printing slug, said matrix being divided into two

separable parts each carrying a variant of the characters capable of being produced. 10

In testimony whereof I have affixed my signature in presence of two witnesses.
